[57] CLAIM

The ornamental design for a handle for cookware or the
like, as shown and described.

DESCRIPTION

FIG. 1 is a side elevational view of a handle for cookware or the like showing my new design, the ornamentation thereof being continuous about the circumference;

FIG. 2 is an end elevational view, taken from the right side thereof; and

FIG. 3 is an end elevational view, taken from the left side thereof.

The broken line showing of a fragment of a cooking pan and handle attachment in FIG. 1 is illustrative of environmental structure only and forms no part of the claimed design.
